Primary Examiner — Paula Allen Greene(74) *Attorney, Agent, or Firm* — Amin, Turocy & Watson,
LLP(57) **CLAIM**

The ornamental design for a headphone, as shown and described.

DESCRIPTION

FIG. 1 is a first perspective view of a headphone.

FIG. 2 is a second perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a right side elevation view thereof; and,

FIG. 8 is a left side elevation view thereof.

The broken lines immediately adjacent the shaded areas represent boundaries of the claimed design while all other broken lines are environment; the broken lines form no part of the claimed design.

1 Claim, 8 Drawing Sheets(56)
